UNITED STATES PATENT OFFICE.

ALBERT Z. SEROR AND EDWARD J. HOYER, OF CHICAGO, ILLINOIS.

DESIGN FOR A FAN.

51,270.

Specification for Design. Patented Sept. 11, 1917.

Application filed June 21, 1916. Serial No. 105,074. Term of patent 7 years.

To all whom it may concern:

Be it known that we, ALBERT Z. SEROR and EDWARD J. HOYER, citizens of the United States, and residents of Chicago, in the county of Cook and State of Illinois, have invented a new, original, and ornamental Design for a Fan, of which the following is a specification, reference being had to the accompanying drawing, forming part thereof.

The figure is a perspective view of a fan embodying our design.

We claim:

The ornamental design for a fan, as shown.

ALBERT Z. SEROR.
EDWARD J. HOYER.
